FUEL BURNER

Oliver F. Campbell, Whiting, Ind., assignor to
Sinclair Refining Company, New York, N. Y.,
a corporation of Maine

Application February 17, 1942, Serial No. 431,233

5 Claims. (Cl. 110—104)

This invention relates to fuel burners and more particularly relates to an improved burner especially adapted to the burning of finely divided solid fuels, such as powdered coal, and capable of operating efficiently over a broad range of capacities.

The improved burner of my present invention is especially designed to inject into the combustion zone of the furnace with which it is used a relatively broad, thin stream of a suspension of solid fuel in a gaseous medium, for example powdered coal suspended in air. This fuel stream may be directed along a generally horizontal or vertical plane or at an angle therewith and a particular advantage of my improved burner is its ability to direct and to shape the resultant flame in a manner best suited to the design of the particular furnace with which it is used.

In the burning of finely divided solid fuels, the fuel is usually supplied to the burner suspended in air. The stream of air in which the fuel is suspended constitutes a portion of the air required for combustion of the fuel. However, additional air is required for combustion and this additional air is herein designated "secondary air".

A serious disadvantage of conventional burners for burning a powdered solid fuel has been the narrow range of capacities at which the burner could be operated at maximum efficiency. For efficient operation, it is essential that the relative proportions of fuel and air be maintained at an optimum value and that the fuel and air be intimately admixed upon entering the combustion zone.

Some fuel burners are adapted to operate efficiently only at a given capacity or at a capacity which cannot be changed while the burner is in operation. The capacity of other conventional burners may be changed at will over a limited range by varying the amount of fuel and combustion air injected thereby into the combustion zone. In the latter type of burner, when it becomes desirable to increase the rate of heating of a boiler, for instance, the rate at which fuel is supplied to the combustion zone by the burner, is increased and, when a lower rate of heating is desired, the rate at which the fuel is supplied is decreased.

If efficient operation is to be maintained over a range of heating rates, these variations in the rate of fuel supply must be accompanied by the appropriate change in the amount of air supplied by the burner. However, it is not alone

sufficient that the optimum proportions of fuel and air be maintained. It is also essential to efficient combustion that the fuel and air be properly mixed, that the fuel be highly dispersed in the combustion air.

One of the major defects of conventional burners has been their failure to accomplish proper mixing of the fuel and air except when operating within a rather narrow range of capacities. Usually such burners depend to a considerable extent upon turbulence caused by the velocities of the fuel stream and the incoming air to effect proper mixing of the air and fuel. In conventional burners the ducts through which the air passes to the combustion zone are usually of a fixed size and, while effective mixing may be obtained within fixed limits, when the burner is operating at lower capacity the velocities are too low to accomplish adequate mixing, and poor combustion results. If an attempt is made still further to decrease the capacity of such burners, a lower limit is soon reached beyond which ignition cannot be maintained.

Burners having air ducts of fixed cross-sectional area may, of course, be designed for low capacity operation. However, if one attempts to operate such low capacity burners at considerably higher capacities either sufficient air cannot be supplied for efficient combustion or the velocity of the air stream is apt to be so great as to extinguish the flame.

Numerous attempts have been made to overcome the capacity range deficiency of conventional fuel burners. For instance, it has been proposed to increase the flexibility of the burners with respect to capacity range by providing mechanical means for varying the cross-sectional area of the air duct at the point where it enters the mixing zone. Thus, when decreased volumes of air are required, the cross-sectional area of the air duct exit would be decreased so as to maintain velocity and turbulence of the air stream at the point where it meets with the fuel stream. One of the primary difficulties with such previously proposed arrangements has been the necessity of having moving parts located within the zone of high temperature where they soon cease to function and another has been their inability adequately to extend the range of efficient operating capacities.

Further attempts to extend the capacity range of conventional burners have led to the suggestion that a plurality of air ducts be provided with means removed from the heating zone for controlling the passage of air through the respec-

tive ducts. However, such suggestions, so far as I am aware, have not heretofore resulted in a burner having the flexibility and other advantageous characteristics combined in the burner of my present invention.

In my co-pending application Serial No. 389,518, filed April 21, 1941, (now Patent No. 2,334,314 issued November 16, 1943) I have described and claimed an improved burner provided with a plurality of co-axially arranged ducts of annular cross-section and co-axially positioned with respect to the fuel injection means. The passage of air through the respective ducts of the burner there described is controlled by a damper adapted to permit the passage of air first through the innermost duct only and progressively through additional adjacent outer ducts as the damper is moved from the closed to the open position. The burner of the present invention in some respects resembles that of my said co-pending application but it possesses certain additional advantages as will hereinafter appear.

In the operation of the burner of my present invention a stream of finely divided solid fuel suspended in a gaseous medium is injected into the combustion zone of the furnace through a nozzle having an exit port of considerably greater dimension along one plane than along the plane perpendicular thereto, such, for example, as a fishtail or fan-shaped nozzle, so that the fuel suspension enters the combustion zone in a relatively broad, thin stream. The secondary air is supplied through laminated banks of air ducts arranged on each of the broad sides of the fuel nozzle and so positioned with respect thereto as to direct the streams of the secondary air issuing therefrom toward the fuel stream from above and below. The passage of air through the respective ducts is so controlled by dampers, without the high temperature zone, that, when operating at minimum capacity, the secondary air is admitted through the innermost ducts only and, as the operating rate is increased, additional fuel and secondary air being supplied, the secondary air is admitted progressively through additional adjacent outer ducts.

The invention will be further described with reference to the accompanying drawings which represent a specific embodiment of my invention. It will be understood, however, that my invention is not limited to the specific arrangement shown.

Fig. 1 of the drawings is a vertical cross-sectional view of the burner along the line 1-1 of Fig. 2 of the drawings which is a front elevation view thereof. In the respective figures of the drawings, like parts are indicated by like numerals.

In the drawings, the burner housing 1 is shown attached to the wall 2 of a furnace at the firing port 3 by means of brackets 4. Within the burner housing and supported thereby is the burner nozzle 5 through which the fuel suspension is injected into the combustion chamber 6. The fuel suspension is supplied to the burner nozzle 5 in variable quantities, depending upon the operating capacity desired, from any convenient source, not shown, through the conduit 7.

The usual practice in the operation of burners of this type is to reduce the solid fuel to the desired fineness by conventional grinders or the like and to suspend the finely divided fuel in air

prior to its passage to the burners. My present invention is not dependent upon any particular means for effecting the grinding and suspension of the fuel. Various means for accomplishing this purpose and for regulating the rate of supply are well known and need not be described herein.

The nozzle 5 is shown as generally fan-shaped, flaring out laterally and being contracted vertically in the direction at its exit 8 into the combustion zone at which point it assumes a generally rectangular shape, as shown in Fig. 2 of the drawings.

Above and below the nozzle 5 are laminated banks of air ducts 9 each consisting of a plurality of parallel air ducts formed by a plurality of parallel plates 10 and side plates 11. These banks of ducts are so positioned that the parallel planes of the respective ducts form acute angles with the plane of the nozzle and intersect that plane in lines perpendicular to the axis of the nozzle beyond the exit end of the nozzle.

These banks of air ducts 9 are sealed into the firing port 3 by means of plates 12 and side-seal plates 13 so as to avoid the uncontrolled entrance of air to the combustion chamber through openings in the firing port. Extending through the side-seal plates 13 are the lighter ports 14.

The outer ends of these ducts 9 terminate in a register or grating 15 to which the parallel plates 10 are fastened so that the respective ducts register with the openings in the gratings. These registers are in turn supported by the nozzle 30 and the supporting members 16.

The passage of air through the several ducts is controlled by the damper plates 17 adapted to be moved across the registers 15 in the direction of the furnace by means of the rack and pinions 18, shafts 19, bevel gears 20, shafts 21 and the handwheels 22.

In Fig. 1 of the drawings, the dampers 17 are shown in the extreme left position. In this position the entrances to all of the secondary air ducts are closed. As the dampers are moved from this position toward the furnace, the entrances to the innermost ducts only are first opened and, as the damper is moved still further toward the right entrances to successive additional outer ducts, are progressively opened.

It is sometimes desirable, in order better to control the flow of air throughout the width of the ducts, to subdivide the respective ducts into a plurality of restricted paths such as by means of division members shown in Fig. 2 of the drawings at 25 supported between the parallel plates forming the duct. These division members may be generally parallel to the vertical plane through the axis of the burner and may be staggered as shown. If desired, these division members may be placed at an angle with said vertical plane so as to concentrate the secondary air at the inner portion or at the outer edges of the flame. These division members also serve to strengthen the duct banks and prevent warping of the plates. If desired, the parallel plates forming the ducts may be supported by tierods.

Also, the inner edges of the plates forming the ducts may be supported by gratings or registers, as indicated in the drawings at 26, for the innermost ducts only. Such registers tend to restrict the exit openings of the ducts and further to increase the velocity of the air stream passing therefrom. This increased velocity is sometimes

desirable, especially with respect to the air stream from the innermost ducts.

The outer ends of the ducts 9 terminate in the air chamber or windbox 23 formed by the burning housing 1. Air may be supplied to the windbox through a suitable opening such as the conduit 24. Where the furnace is to be operated under forced draft conditions, the conduit 24 may be connected with a conventional air propulsion means, not shown, and where natural draft conditions are to be used, the windbox 23 or the conduit 24 may be open to the atmosphere.

In the operation of the burner shown, the fuel suspension supplied to the burner through the conduit 7 under pressure passes through the nozzle 5 and is injected into the combustion zone 6 in a relatively thin fan-shaped stream. This fuel suspension includes a portion of the air required for combustion of the suspended fuel but not the entire requirement. Secondary air is supplied through the laminated duct banks 9 and for maximum combustion efficiency this secondary air must become intimately admixed with the suspended fuel in the combustion zone.

The thoroughness of this mixing is dependent primarily upon the velocity at which the secondary air stream is directed into the fuel suspension stream. Where the quantity of fuel supplied is varied, the amount of secondary air must be varied proportionately in order to obtain the proper combustion mixture. If the velocity of the entering secondary air were dependent solely upon the volume of secondary air required, velocities inadequate for proper mixing would result when the volume of secondary air is reduced to meet reduced fuel injection. In the operation of my improved burner, optimum velocities of the secondary air for proper mixing are obtained over a wide range of operating capacities by increasing or decreasing the number of ducts through which the secondary air is supplied in accordance with the amount of fuel being burned and consequently the amount of secondary air required.

However, control of velocity alone of the entering secondary air stream or streams is not sufficient to effect optimum mixing. The point of introduction of the secondary air stream or streams and the shape of the injected fuel stream are also of major importance. In my improved burner, the secondary air ducts are so positioned with respect to the fuel nozzle as to direct the air streams therefrom into the thin, laterally extended fuel stream from above and below at points near its exit from the fuel nozzle. The amounts of secondary air so directed against the upper and lower sides of the fuel stream may be equal or may be so proportioned as to direct or shape the flame to meet special furnace conditions.

When operating at minimum capacity, the velocity of the incoming fuel stream is naturally reduced. Under such conditions, better mixing is obtained by directing the reduced amount of secondary air into the fuel stream at a point just beyond the exit of the latter from the fuel nozzle. Even when operating at higher capacities, it is desirable to introduce a portion of the secondary air into the fuel stream immediately following the exit of the latter from the fuel nozzle.

In the operation of my improved burner through mixing and maximum combustion efficiency are obtained by reason of its novel combination of advantages derived from the injection of the fuel into the combustion chamber in a

stream having a large surface area per unit of volume and the introduction of the secondary air at the optimum velocity and at the optimum point with respect to the fuel stream.

These dampers as shown in the drawings, are adapted to be individually controlled manually. If desired, the movement of the upper and lower dampers may be correlated by suitable linkages not shown or their movement may be automatically controlled by conventional means responsive to the amount of fuel supply, or the like.

In the drawings, I have shown my improved burner so positioned that the fan-shaped fuel stream therefrom is injected into the combustion chamber in a generally horizontal plane. It will be understood, however, that the position of the burner may be varied to meet the firing or flame-shaping requirements of particular furnaces with which it is to be used.

I claim:

20. 1. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a member adapted to close each of the ducts of the bank when in the extreme closed position, to admit air through each of the ducts of the bank when in the extreme open position and to open first the innermost duct only of the respective banks and progressively to open additional successively outer ducts thereof as the damper member is moved from the closed position to the open position.
25. 2. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
30. 3. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
35. 4. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
40. 5. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
45. 6. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
50. 7. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
55. 8. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
60. 9. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
65. 10. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
70. 11. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.
75. 12. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port, a damper for each bank of air ducts for controlling the passage of air through the respective ducts thereof, said damper comprising a sliding plate member adapted to close each of the ducts of the bank when in the extreme closed position, to admit air through each of the ducts of the bank when in the extreme open position and to open first the innermost duct only of the respective banks and progressively to open additional successively outer ducts thereof as the sliding plate member is moved from the closed position to the open position.

plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port beyond the exit port in lines substantially parallel to the vertical plane of said port, a damper for each bank of air ducts for controlling the passage of air through the respective ducts thereof, said damper comprising a member adapted to close each of the ducts of the bank when in the extreme closed position, to admit air through each of the ducts of the bank when in the extreme open position and to open first the innermost duct only of the respective banks and progressively to open additional successively outer ducts thereof as the damper member is moved from the closed position to the open position.

4. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port beyond the exit port, division members extending through the respective ducts so as to divide the ducts into a plurality of passages running toward the exit ends thereof, a damper for each bank of air ducts for controlling the passage of

air through the respective ducts thereof, said damper comprising a member adapted to close each of the ducts of the bank when in the extreme closed position, to admit air through each of the ducts of the bank when in the extreme open position and to open first the innermost duct only of the respective banks and progressively to open additional successively outer ducts thereof as the damper member is moved from the closed position to the open position.

5. In a fuel burner for burning finely-divided solid fuel suspended in a gaseous medium the improvement which comprises a fuel injection nozzle having a relatively broad, thin exit port, two banks of air ducts each bank comprising a plurality of substantially parallel air ducts substantially co-extensive in breadth with the breadth of the nozzle exit port, one bank being positioned on each of the opposite broad sides of the nozzle exit port so that the parallel planes of the respective ducts form acute angles with the longitudinal plane of the nozzle exit port and intersect said longitudinal plane extended inwardly from said port beyond the exit port, a grating extending across the exit of the innermost ducts so as to restrict the passage of air therefrom, a damper for each bank of air ducts for controlling the passage of air through the respective ducts thereof, said damper comprising a member adapted to close each of the ducts of the bank when in the extreme closed position, to admit air through each of the ducts of the bank when in the extreme open position and to open first the innermost duct only of the respective banks and progressively to open additional successively outer ducts thereof as the damper member is moved from the closed position to the open position.
